UNITED STATES PATENT OFFICE.

GEORGE C. THIESEN, OF BAYONNE, NEW JERSEY.

DESIGN FOR A PITCHER OR SIMILAR ARTICLE.

No. 38,985.

Specification for Design.

Patented Jan. 7, 1908.

Application filed November 27, 1907. Serial No. 404,184. Term of patent 3½ years.

To all whom it may concern:

Be it known that I, GEORGE C. THIESEN, a citizen of the United States, residing at Bayonne, in the county of Hudson, State of New Jersey, have invented a new, original, and ornamental Design for a Pitcher or Similar Article, of which the following is a specification, reference being had to the accompanying drawing, forming part thereof, in which—

Figure 1 is a top view of a pitcher or simi-

lar article, showing my design, and Fig. 2 is a side view of the same.

What I claim is:

The ornamental design for a pitcher or similar article, substantially as shown.

GEO. C. THIESEN.
